ELECTRICAL CONTROL CIRCUITS FOR
THERMIONIC RECTIFIERS

Daniel Edward O'Donovan, Chelmsford, England,
assignor to Radio Corporation of America, a
corporation of Delaware

Application November 10, 1932, Serial No. 641,954
In Great Britain November 20, 1931

12 Claims. (Cl. 175—363)

This invention relates to electrical control circuits and more particularly to electrical control circuits for use in connection with thermionic rectifiers and the like and especially though not 5 exclusively, to mercury vapour hot cathode rectifiers.

As is well known, it is very desirable that the anode supply to thermionic rectifiers, such as mercury vapour hot cathode rectifiers, should not 10 be switched on until the cathodes have reached a predetermined working temperature, and the present invention has for its object to provide an improved automatic control circuit of simple and economical construction and adapted to occupy 15 comparatively small space, for performing the protective function in question.

According to this invention, a control circuit for protecting a thermionic rectifier or like device in the manner described comprises a comparatively slow acting thermostatic relay, a contact closed by said relay when said relay is cold and adapted to complete the circuit of a quick acting relay, a contact closed upon energization of the 20 said quick acting relay and connected in parallel with said first mentioned contact, a further contact adapted to be closed upon energization of the quick acting relay and connected to complete a heating circuit for the thermostatic relay and two further contacts in series with one another 25 in an anode potential supply lead for the thermionic rectifier or the like, one of said last mentioned contacts being adapted to be closed by the quick acting relay when energized and the other being adapted to be closed by the thermostatic relay when hot.

The invention is illustrated in the accompanying drawing which shows one way of carrying out the invention as applied to a full wave mercury vapour hot cathode rectifier.

Referring to the drawing potential is supplied to 40 the anodes 1, 2 of the rectifier 3 through a transformer 4 having a centre tapped secondary in the usual way, the primary of said transformer being connected across the mains M or other energy supply through a manually operable main switch 45 5 and through two contacts T₁ R₁ in series. The contact T₁ is adapted to be closed by a thermostatic relay T consisting of a bimetallic strip, the said contact being closed when the relay is hot. 50 The other contact R₁ is adapted to be closed by a quick acting relay R whose winding is energized from the supply through a second contact T₂ of the thermostatic relay, and adapted to be closed when said relay is closed. There is also 55 provided a maintaining contact R₂ in parallel

with the contact T₂ said maintaining contact being adapted to be closed by the quick acting relay R when energized. The circuit for the winding of the quick acting relay is completed through the primary 6 of a transformer having two secondaries, one secondary 7 being centre tapped and serving as in the usual way for heating the filaments 8 of the rectifier, and the other secondary 9 serving to supply heating current for the thermostatic relay, the heating circuit extending from the secondary through the bimetallic strip, through a further contact R₃, adapted to be closed when the quick acting relay is closed, and thence back to the heating secondary 9.

It will be seen that with this arrangement, assuming the bimetallic strip to be cold, when the master switch 5 is closed a circuit will be made through the winding of the quick acting relay R via the primary 6 and through the contact T₂. The quick acting relay will, therefore, be energized and will close all its contacts, the contact R₃ completing the heating circuit for the bimetallic strip, the contact R₂ maintaining the circuit for the winding of the quick acting relay, and the contact R₁ being in the 20 anode supply lead to the primary of the transformer 4. The bimetallic strip will therefore be heated and will bend, opening the contact T₂ through which the quick acting relay circuit was originally made and closing the contact T₁ in the anode supply circuit. Power will therefore be applied the rectifier. If now the high tension supply fails, or if the main switch is 25 opened, the quick acting relay will be deenergized and cannot be reenergized until the bimetallic strip has cooled down sufficiently to reach its cold position, and close the contact T₂ in parallel with the maintaining contact R₂ for the quick acting relay.

It will be seen therefore that the arrangement 30 provides the following features of inherent protection automatically:

(1) The anode supply transformer cannot be 35 energized until a certain time delay has elapsed after switching on the filament, this time delay being of course determined in accordance with the protective requirements of the rectifier to be protected, and,

(2) The high tension supply transformer is 40 disconnected substantially instantly if the power supply is interrupted, and if this occurs 45 the supply to the anode energizing transformer cannot be reconnected until the thermostatic relay has cooled and been heated again.

Having now particularly described and ascer- 50

tained the nature of my said invention and in what manner the same is to be performed, I declare that what I claim is:—

1. A control circuit for protecting a thermionic rectifier or like device from having anode potential applied thereto before a predetermined cathode temperature has been reached, said control circuit comprising a comparatively slow acting thermostatic relay, a contact device closed by said relay when said relay is cold and adapted to complete the circuit of a quick acting relay, a contact device closed upon energization of the said quick acting relay and connected in parallel with said first mentioned contact device closed upon energization of the quick acting relay and connected to complete a heating circuit for the thermostatic relay and two further contact devices in series with one another in an anode potential supply lead for the thermionic rectifier or the like, one of said two further contact devices being closed by the quick acting relay when energized and the other being closed by the thermostatic relay when hot.

2. A control circuit as claimed in claim 1 and 25 in which the thermostatic relay comprises a bimetallic strip.

3. A control circuit for thermionic rectifiers having a slow thermostatic acting relay and a quick acting relay for actuating the controlled rectifier circuit, comprising a transformer having its secondary to supply anode potential to the rectifier to be protected, and having its primary connected to a source of supply through a contact device closed when the thermostatic relay is hot and through a second contact device in series with said first mentioned contact device and closed when the quick acting relay is energized; a second transformer having a secondary connected to supply cathode heating potential to the rectifier or the like to be protected and a further secondary adapted to supply heating potential to the thermostatic relay, the primary windings of said second transformer being energized from the source of supply in series with the winding of the quick acting relay and a contact device adapted to be closed when said quick acting relay is energized; a further contact device closed when the thermostatic relay is cold and connected in shunt across the last mentioned contact device closed by the quick acting relay; and an additional contact device closed when the quick acting relay is energized and connected in series with the thermostatic relay and the transformer secondary for supplying heating current thereto.

4. A control circuit for thermionic apparatus, means for protecting said apparatus until a predetermined cathode temperature has been attained, said means comprising a comparatively slow acting relay, a contact device closed by said relay when said relay is cold, and adapted to complete the circuit of a quick acting relay, a contact device connected in parallel with said first mentioned contact device closed upon energization of the quick acting relay and connected to complete a circuit for said slow acting relay, and a plurality of contacts connected in series with one another in the anode supply lead of the thermionic apparatus, at least one of said series contacts being closed by said quick acting relay when energized, and at least one other of said series contacts being closed when said slow acting relay is heated to a predetermined temperature.

5. A control circuit for thermionic apparatus, 75 means for protecting said apparatus until a pre-

determined cathode temperature has been attained, said means comprising a comparatively slow acting thermostatic relay, a contact device closed by said relay when said relay is cold, and adapted to complete the circuit of a quick acting relay, a contact device connected in parallel with said first mentioned contact device closed upon energization of the quick acting relay and connected to complete the heating circuit for said slow acting thermostatic relay, and a plurality of contacts connected in series with one another in the anode supply lead of the thermionic apparatus, at least one of said series contacts being closed by said quick acting relay when energized, and at least one other of said series contacts being closed by said slow acting thermostatic relay when hot.

6. A control circuit for thermionic apparatus, means for protecting said apparatus until a predetermined cathode temperature has been attained, said means comprising a comparatively slow acting thermostatic relay comprising a bimetallic strip, a contact device closed by said relay when said relay is cold, and adapted to complete the circuit of a quick acting relay, a contact device connected in parallel with said first mentioned contact device closed upon energization of the quick acting relay and connected to complete the heating circuit for said slow acting thermostatic relay, and a plurality of contacts connected in series with one another in the anode supply lead of the thermionic apparatus, at least one of said series contacts being closed by said quick acting relay when energized, and at least one other of said series contacts being closed by said slow acting thermostatic relay when hot.

7. A control circuit for thermionic apparatus, means for protecting said apparatus until a predetermined cathode temperature has been attained, said means comprising a comparatively slow acting thermostatic relay comprising a bimetallic strip which is directly heated by an electric current flowing therethrough, a contact device closed by said relay when said relay is cold, and adapted to complete the circuit of a quick acting relay, a contact device connected in parallel with said first mentioned contact device closed upon energization of the quick acting relay and connected to complete the heating circuit for said slow acting thermostatic relay, and a plurality of contacts connected in series with one another in the anode supply lead of the thermionic apparatus, at least one of said series contacts being closed by said quick acting relay when energized and at least one other of said series contacts being closed by said slow acting thermostatic relay when hot.

8. A control circuit for thermionic apparatus, means for protecting said apparatus until a predetermined cathode temperature has been attained, said means comprising a comparatively slow acting thermostatic relay comprising a bimetallic strip, a contact device closed by said relay when said relay is cold, and adapted to complete the circuit of a quick acting electromagnetic relay, a contact device connected in parallel with said first mentioned contact device closed upon energization of the quick acting electro-magnetic relay and connected to complete the heating circuit for said slow acting thermostatic relay, and a plurality of contacts connected in series with one another in the anode supply lead of the thermionic apparatus, at least one of said series contacts being closed by said quick acting electro-magnetic relay when energized, and at least one other of said series contacts being closed by said slow acting thermostatic relay when hot.

said series contacts being closed by said slow acting thermostatic relay when hot.

9. A control circuit for thermionic apparatus, means for protecting said apparatus until a predetermined cathode temperature is attained, said means comprising an anode supply circuit, a slow acting relay for closing, a switch connected in series with the anode supply circuit, a quick acting relay for closing a second switch also connected in series with the anode supply circuit of said apparatus.

10. A control circuit for thermionic rectifier apparatus, means for protecting said rectifier apparatus until a predetermined cathode temperature is attained, said means comprising an anode supply circuit, a slow acting thermostatic relay for closing a switch connected in series with the anode supply circuit, a quick acting electro-magnetic relay for closing a second switch also con-

nected in series with the anode supply circuit of said apparatus.

11. A control circuit for a rectifier comprising a plurality of series switches for controlling the anode supply of said rectifier, at least one of said switches connected in series with an anode supply circuit and operated by a thermostatic relay and at least one of the other switches also connected in series with said anode supply circuit and operated by an electro-magnetic relay.

12. A control circuit for a thermionic device comprising a plurality of series switches for controlling the anode supply of said thermionic device, at least one of said switches connected in series with said anode supply and operated by a slow acting thermostatic relay and at least one of the other switches also connected in series with said anode supply and operated by a quick acting electro-magnetic relay.

DANIEL EDWARD O'DONOVAN.
